UNITED STATES PATENT OFFICE.

JAMES V. CULLEN, OF CHICAGO, ILLINOIS.

VEHICLE LIFTING DEVICE.

Application filed April 18, 1922. Serial No. 554,598.

To all whom it may concern:

Be it known that I, JAMES V. CULLEN, a citizen of the United States, residing at Chicago, in the county of Cook and State of

Illinois, have invented new and useful Improvements in Vehicle Lifting Devices, of which the following is a specification.

This invention relates to hoists or lifting devices and more particularly to a structure designed for hoisting automobiles to a desired elevation to permit convenient working on the parts of the machine which are accessible only from beneath the machine.

Another object of the invention is to provide a hoisting device as specified which is comparatively simple in construction, is strong and durable and by means of which a motor vehicle may be raised, by one person and which lifting mechanism is also designed to permit the lifting of one end of the vehicle at a higher elevation than the other end of desired.

Other objects of the invention will appear in the following detailed description taken in connection with the accompanying drawings wherein:

Fig. 1 is a side elevation of the improved lifting device.

Fig. 2 is an end elevation of the lifting device.

Fig. 3 is a fragmentary vertical section taken on the line 3—3 of Fig. 2.

Fig. 4 is a fragmentary vertical section taken on the line 4—4 of Fig. 2.

Referring more particularly to the drawings, the improved vehicle lifting device comprises substantially frusto triangularly shaped end supports 1 and 2 which are arranged in pairs at the ends of the lifting device and which are connected at their base by longitudinally extending supporting bars 3 and at their tops by supporting bars 4. The supporting bars 3 and 4 are braced intermediate their ends by vertical bracing bars 5.

Each of the substantially frusto triangular supports 1 and 2 has a guide structure 6 extending vertically therethrough at their altitudes and these guide structures each comprises spaced angle irons 7 and 8 having parallel facing surfaces between which the ends of the lifting bars 9 extend as clearly indicated in Figs. 2 and 4 of the drawings. The lifting bars 9 are connected by longitudinally extending vehicle supports 10 one of which is positioned at each side

of the lifting device adjacent the guides 6. Substantially U shaped clips 11 engage about the lifting bars 9 adjacent to the guides 6 and they have bolts or pins 12 carried thereby upon which connecting loops 13 are mounted. A set of elevating cables or ropes 14 are connected to the pins 12 carried by the clips 11 which are in turn connected to or mounted upon the lifting bar 9, move through the guides 6 carried by the end supports 2 and these cables extend upwardly along the guide 6 and over sheaves 15, extending downwardly therefrom, about sheaves 16 and extending from the sheaves 16 parallel with the base of the lifting device to the outer lower corners of the end supports 1 where they pass about guiding sheaves 17, extending upwardly from the sheaves 17 to the drums 18 to which they are connected for winding thereon. The sheaves 15, 16 and 17 are supported by suitable supporting shafts 19 as clearly shown in Fig. 2 of the drawings. A second set of elevating cables or ropes 20 are connected to the drums 18 for winding thereon and extend upwardly from the drums about guiding sheaves 22 rotatably supported by suitable shafts 23 at the tops of the supports 1. From the guiding sheaves 22, the cables 20 extend downwardly and are connected to the clips 11 which engage about the lifting bar 9 movable between the guides 6 of the end supports 1.

The drums 18 are mounted upon a shaft 24 which is rotatably supported by suitable bearings 25 which are in turn carried by the outer sides of the end supports 1. The shaft 24 has a relatively large gear 26 mounted thereon which meshes with a pinion 27 carried by an auxiliary shaft 28. A crank handle 29 is mounted upon the shaft 28 to permit manual rotation of the shaft and consequently manual rotation of the shaft 24 at an increased power and decreased speed through the medium of the gear 26 and pinion 27. A suitable pawl 30 is provided which engages the teeth of the pinion 27 to prevent back rotation of the pinion and consequently unwinding rotation of the drums 18.

A suitable incline (not shown) may be provided for permitting a vehicle to be driven upon the vehicle supports 10 and then by winding rotation of the drums 18, these vehicle supports, and the vehicle supported thereon may be raised to any desired eleva-

tion within the limits of the guides 6, to support the vehicle high enough to permit a workman to conveniently work on the parts underneath it. The angle bars 7 and 8 of the guides 6 are provided with a plurality of spaced openings 32 which are adapted to receive bolts or pins 33 upon which the lifting bars 9 rest, the said bolts cooperating with the respective ropes or cables 14 or 20 for holding the vehicle in its raised position. Diagonal braces 34 and 35 are provided for bracing and connecting the end supports 1 and 2 and these braces are connected to the end supports by removable lower bolts 36 and upper bolts 37. When a vehicle is driven upon the lifting device the bolts 37 are removed, and the central connecting bolt 38 is also removed after which the braces are moved downwardly, pivotally upon the bolts 36 to permit the vehicle to be driven upon the vehicle supports 10 after which the braces 34 and 35 are raised and extend diagonally, crossing each other intermediate their ends and the bolts 37 and 38 are then adjusted to securely hold the braces in place. However, in case it is desired to work upon the ends of the vehicle, at which time the diagonally extending braces would be in the way, these braces are positioned horizontally and they are provided with bolt receiving openings 39 so that when positioned horizontally the bolts 36 will be inserted through the brace 35, for securely connecting it in a horizontal position to either the end braces 1 or 2 while the brace 34 is attached to the end braces 1 or 2 by the upper bolts 37. It is desirable to provide two of the openings 39 in each of the braces 34 or 35 so that either of them may be supported in the upper or lower horizontal position as desired.

In Fig. 1 of the drawings, the vehicle supports 10, are shown in dotted lines, supported at an incline so as to permit one end of the vehicle to be raised higher than the opposite end and such adjustment is permitted by disconnecting the loops 13 from

the pins 12 and clips 11 at the ends of the supports which are not to be raised and thus by rotating the drums 18 in winding rotation, only one end of the vehicle will be lifted. 50

It is, of course, to be understood that the invention may be constructed in other manners and the parts associated in different relations and, therefore, I do not desire to be limited in any manner except as set forth in the claims hereunto appended. 55

Having thus described my invention what I claim is:

1. In a vehicle support, a plurality of substantially frusto triangular shape end supports, braces connecting said supports, a pair of vertical guides carried by each of said supports, lifting bars having their ends seated in said guides, vehicle supporting bars carried by said lifting bars, cables detachably connected to said lifting bars, winding drums, means for rotating said winding drums to wind said cables thereon or unwind therefrom for raising or lowering said lifting bars and vehicle supporting bars. 60

2. In a vehicle support, a plurality of substantially frusto triangular shape end supports, braces connecting said supports, a pair of vertical guides carried by each of said supports, lifting bars having their ends seated in said guides, vehicle supporting bars carried by said lifting bars, cables detachably connected to said lifting bars, winding drums, means for rotating said winding drums to wind said cables thereon or unwind therefrom for raising or lowering said lifting bars and vehicle supporting bars, and bracing bars detachably connected to the outer sides of said substantially triangular end supports, and adapted to be connected to the end supports in diagonal relation or in parallel horizontal relation. 65

In testimony whereof I affix my signature.

JAMES V. CULLEN.
